UNITED STATES PATENT OFFICE

107,687

DESIGN FOR A COMBINED WATCH AND MIRROR WITH HOLDER THEREFOR

Joseph Lipschutz and Harry C. Ruger, Brooklyn,
N. Y.

Application June 24, 1937, Serial No. 70,046

Term of patent 7 years

To all whom it may concern:

Be it known that we, Joseph Lipschutz and Harry C. Ruger, citizens of the United States, residing at 450 Ocean Parkway, and 454 East 7th Street, respectively, in the Borough of Brooklyn, city of New York, county of Kings, and State of New York, have invented a new, original, and ornamental Design for a Combined Watch and Mirror with Holder Therefor, of which the following is a specification, reference being had to the accompanying drawing, forming part thereof.

Figure 2 is a plan view of the same in an open position, disclosing the time keeping element;

Figure 3 is a plan view of the case in an open position showing the appearance of the opposite side of Figure 2; and

We claim:

The ornamental design for a combined watch and mirror with holder therefor, as shown and described.

JOSEPH LIPSCHUTZ.
HARRY C. RUGER.
